UNITED STATES PATENT OFFICE.

ROY W. SCHWEIKER, OF LANSDALE, PENNSYLVANIA.

LIGHTING FIXTURE.

Application filed August 12, 1926. Serial No. 128,851.

This invention relates to lighting fixtures and, more particularly, to an improved means for holding the lamp socket in position on the fixture, especially in a fixture 5 of porcelain or similar material, although it is to be understood that the invention is not limited in that respect.

The object of the invention is to provide a simple, inexpensive, easily applied and 10 moved fastening means by which the lamp socket may be mounted and secured in the fixture without liability of loosening, turning, or displacement.

In carrying out the invention I provide 15 two rings, adapted to be located on opposite sides of the flange within the fixture and to be clamped between the sections of the lamp socket when they are connected, means being provided to prevent the rings from 20 turning and also to prevent the socket from turning.

The rings are so constructed that when 25 the sections of the socket are screwed up, certain parts are flexed and a very secure fit is obtained.

A practical embodiment of the invention 30 comprises an outer ring which has projections, thus enabling the projections to be cut down to snugly fit the inside of the porcelain fixture and to center this ring even 35 though the cavity in the fixture varies in size; and an inner ring provided with points or projections, enabling one of them to be bent down into a notch provided for 40 its reception in the flange on the fixture, thereby preventing rotation of the rings. This inner ring also has a projection to fit 45 into a notch in the inner section of the insulating part of the lamp socket to prevent the insulating socket from turning. The inner ring and the points or projections are 50 arranged in offset relation to each other, being connected by a shoulder which allows the two rings to come closely together but does not permit them to interfere with the tension which is exerted on them by the screwing together of the sections of the lamp socket.

In the accompanying drawings: 55 Figure 1, is a front elevation, partly in section;

Fig. 2, is a vertical section;

Fig. 3, is a rear view, parts of the sectional lamp socket being broken away;

Fig. 4, is an edge view, broken away, of 55 the inner ring;

Fig. 5, is a front face view thereof; and

Fig. 6, is a face view of the outer ring.

The porcelain fixture 1 is of the same general type as illustrated in certain of my 60 earlier applications for patent but the design thereof does not enter into the present invention. This fixture is provided with an inner flange 2 and a recess or cavity 3.

The lamp socket, as illustrated, comprises 65 inner and outer porcelain sections 4 and 5, and a shell 6 of ordinary construction into which the electric bulb screws, these sections being adapted to lie on opposite sides of the flange 2; the outer part 5 having 70 screw threads which engage the shell 6, thus enabling the sections to be screwed up to clamp against the flange 2 the two rings 7 and 8 which lie on opposite sides of said flange, said rings constituting my present 75 invention.

The outer ring 7 is preferably of metal 80 having a certain degree of inherent resiliency. Said ring has fins, points, or projections 9 which are originally of a sufficient length to enable them to be cut off to the desired extent by a pair of shears so that they will snugly fit within the recess or cavity 3 and engage the wall thereof. This enables the ring 7 to be centered in the 85 cavity and to be sprung into position regardless of any irregularities existing in the walls of the cavity.

The inner ring 8 is provided with a struck-up lug or fin 10 for reception in a notch 11 90 in the section 4 to prevent the ring 8 from turning. This feature by itself is not novel with me and no claim is made to it per se.

The ring 8 is provided with quite a number 95 of fins or projections 12 which are connected by an offset part 13 or shoulder to the ring 8. This enables the ring 8 to be drawn snugly against the rear of the flange 2 all the way around and also insures that one of the fins will be closely related to a notch 14 100 provided in the flange 2 so that it may be bent down into said notch as shown at 15 to thereby prevent the ring 8 and hence the socket and the outer ring 7 from turning within the fixture because the screwing up of the outer part 5 of the socket tensions the two rings 7, 8 and holds them snugly against 105 opposite sides of the flange 2. The inner

ring 8 being locked against rotation and the inner section 4 being locked against rotation relative to the ring 8, the tension prevents any of the parts from turning. The shoulder which is provided on the ring 8 enables the rings 7 and 8 to lie close together when under tension, thus making a snug and secure joint.

My improvements have many advantages
10 and in addition to those previously set forth, there remains the fact that it is unnecessary to provide any bolts, screws, nuts or other special fastenings to hold the sections of the lamp socket in position. When the rings are
15 located, the screwing up of the sections of the socket automatically tightens the parts and results in a secure connection. It is then only necessary, when it is desired to disconnect the sections of the socket, to unscrew
20 the outer section 5.

What I claim is:

1. In a lighting fixture, the combination
25 with a fixture shell or body having lamp
socket engaging means, of a sectional lamp
socket, and rings held between the sections
of said socket, one of said rings being pro-
30 vided with means engaging the fixture to
prevent rotation of said ring, and also hav-
ing means to engage the lamp socket to pre-
vent said socket from turning, said rings be-
ing located on opposite sides of the engag-
35 ing means aforesaid and clamped there-
against by the tension exerted on them by
the sections of the socket.

2. In a lighting fixture, the combination
40 with a fixture shell or body having a recess
or cavity and an internal flange, of a section-
al lamp socket, and two rings held between
the sections of said socket, one ring being
45 provided with outstanding fins or projections
bearing on the flange aforesaid and also

adapted to bear on the wall of said cavity
to center said ring, the remaining ring being
provided with fins which bear on the oppo-
45 site side of the flange, one of said fins hav-
ing a locking engagement with the fixture
to prevent rotation of said ring, said rings
being clamped against opposite sides of the
flange by the tension exerted on them by
the sections of the socket. 50

3. Means for mounting a sectional electric
lamp socket on a support, comprising a pair
of flexible clamping rings, one of which has
projections to center and hold it in position
on the object on which the lamp socket is
55 to be mounted, the other ring being pro-
vided with shouldered fins or projections,
one of which may be made to lock with the
object on which the lamp socket is to be
mounted, thereby to prevent turning of the
60 rings, said rings being adapted to be ten-
sioned by the tightening of the sections of
the aforesaid lamp socket.

4. The combination with an apertured ob-
ject, of a sectional electric lamp socket, and
means for mounting the lamp socket in said
apertured object, comprising a pair of flex-
ible clamping rings having parts thereof lo-
70 cated between the sections of the lamp socket
and adapted to be tensioned thereby, said
rings being located on opposite sides of the
object where the aperture is located and both
engaging said object, one of said rings being
75 provided with projections, the other ring
having shouldered fins, one of said fins being
utilizable as a means to lock with the object
aforesaid, said rings being clamped against
the object by the tensioning action of the
parts of said socket. 75

In testimony whereof I affix my signa- 80
ture.

ROY W. SCHWEIKER.
